(CL. D14—3)

FIG. 1

FIG. 2

FIG. 3

FIG. 4

FIG. 5

FIG. 7

FIG. 6

FIG. 1 is a side elevational view of one side of a compactor vehicle in accordance with my new design;

FIG. 2 is a top plan view;

FIG. 3 is a front elevational view;

FIG. 4 is a rear elevational view;

FIG. 5 is a side elevation of the side opposite that shown in FIG. 1, with portions of the scraper blade assembly broken away for convenience of illustration;

FIG. 6 is a perspective view as seen from the top and left of FIG. 3 and from the top and right of FIG. 5, with the compactor vehicle in a right-hand turn and with the scraper blade assembly and roller feet removed for convenience of illustration; and

FIG. 7 is a perspective view as seen from the bottom and left of FIG. 1 with the scraper blade assembly and roller feet removed for convenience of illustration.

The dominant features of my design reside in the portions shown in full lines.

I claim:

The ornamental design for a compactor vehicle, as shown and described.
